[57] CLAIM

The ornamental design for a combined iron and base therefor, substantially as shown.

DESCRIPTION

FIG. 1 is a front perspective view of the combined iron and base therefor showing our new design;

FIG. 2 is a side elevational view thereof, the opposite side being a mirror image thereof;

FIG. 3 is a front elevational view thereof;

FIG. 4 is a rear elevational view thereof;

FIG. 5 is a top plan view thereof;

FIG. 6 is a bottom plan view thereof.

FIG.1

FIG.2

FIG.3

FIG. 4

FIG. 5

FIG. 6
